ABSTRACT: A shift register employing a three input AND element, the outputs of which may be used as controls of a conventional fluidic flip-flop. By using the three element AND gate, the power levels of the controls will be sufficiently high to switch the flip-flop in the presence of the trigger signal and will not be sufficient in the absence of the trigger. Additional power sources are, therefore, unnecessary.

FIG. 1

FIG. 2

Charles J. Ahern
INVENTOR.

BY

W. Ahern

FLUIDIC SHIFT REGISTER

BRIEF SUMMARY OF INVENTION

This invention relates to fluidic devices having no moving parts and relates particularly to fluidic shift registers where information available in fluid pulse form is to be stored. The prior art shows that this storage may be made by setting the output of a bistable fluidic flip-flop and shows many schemes of getting this information to the flip-flop.

In those devices which wish to register the coincidence of two or more signals or combinations thereof, the prior art teaches the use of two passive AND gates to register the coincidence of either of two signals with a trigger or clock pulse signal. The output of the AND gate arrangement is then used to set the flip-flop. This has the drawback that there must be exact coincidence or the output of the AND gate may be insufficient to switch the flip-flop. Since the signals used by the AND gates are unamplified, they must be quite large or there would be the danger that the output of the AND gate would be insufficient to switch the flip-flop and anything less than exact coincidence would cause the output to be less than optimum. As successive passive elements are staged, their losses increase thereby heightening the problems of the AND element shift register.

The prior art also teaches the use of active OR gates to establish the occurrence of coincidence and then using the output of the OR gate to control switching of the flip-flop. This has the obvious disadvantage of requiring one or more additional sources of pressurized fluid. In light of the difficulties associated with these prior art devices, it is an object of the present invention to provide a shift register for fluid systems which has low power consumption and accuracy of operation. It is also an object of this invention to provide a shift register for fluid systems which can accept input signals of normal level and which does not require that these signals be amplified.

It is a further object of this invention to provide a fluid shift register to record the coincidence of fluidic pulse events which is inexpensive to manufacture and does not require perfect simultaneity of events. It is a further object of this invention to provide a fluidic shift register which will recognize as a coincidence of events, events having a small time delay between respective initiating fluid surges.

It is also an object of the invention to provide a multiple input AND gate adapted for use with a bistable flip-flop to form a simple and direct shift register for fluid systems.

These and other objects will be obvious to the man skilled in the art from the appended drawing and claims.

BRIEF DESCRIPTION OF DRAWING

FIG. 1 is the fluidic circuit diagram of the device made according to the present invention.

FIG. 2 is a schematic of one embodiment of a device having the circuit diagram of FIG. 1.

DETAILED DESCRIPTION

Referring now to FIG. 1, the fluidic circuit is shown as having an input region 1 with three fluid inputs 10, 12, and 14. These inputs 10, 12, and 14 can combine to follow either of the flow paths 16 or 18. Shown in flow paths 16 and 18 are amplitude reducing means shown as flow restrictions 20 and 22. These flow restrictions 20 and 22 are used to represent any means which may be used to decrease the amplitude of any signals in flow paths 16 and 18.

Downstream of the restrictions 20 and 22 is a conventional bistable flip-flop shown generally as 24. The flip-flop 24 has a source of pressurized fluid 26 and two output legs 28 and 30. The control for the flip-flop 24 is provided by the outlets of flow paths 16 and 18.

For a full understanding of my invention and referring to the specific embodiment of FIG. 2, the preferred embodiment of my device is set forth below. The numbering of the FIG. 2 embodiment corresponds to the numbering of the FIG. 1 circuit

wherever possible, but is in the 100 series of numbering. The input region 101 has three input passages 110, 112 and 114 which meet at a common interaction chamber 113. Disposed in a generally intercepting relationship with two of the input passages 110 and 114 are two additional passages 116 and 118. A third passage 117 is also shown connecting the reaction region to a vent or fluid dump 111 to provide a flow path for any excess fluid which may tend to accumulate in the fluid interaction chamber 113.

10 The flip-flop 124 is a bistable device in which the information to be stored causes fluid flow from the input 126 to be channeled through one or the other of output passages 128 or 130. Input 126 is in communication with a source of fluid under pressure, P_x . The flip-flop 124 is controlled by fluid flow in passages 116 and 118, the outlets of which are arranged in the usual fashion on either side of the fluid stream issuing from inlet 126 and upstream of the output passages 128 and 130.

The passages 116 and 118 contain flow restrictions 120 and

15 122 which are operative to reduce the amplitude of any signals present in the passages 116 and 118. Since shift registers are used to record which of two possible conditions exist at a discrete time interval and at a specific point in the circuit, the restrictions are designed to reduce the level of the signal present in passages 116 and 118 below the switching level of

20 the flip-flop 124 whenever that signal is merely the signal input in either of passages 110 or 114. Further, this reduction need only be sufficient to prevent the single signal from

25 passage 110 or 114 from changing the state of the flip-flop by itself. Because of the particular use that shift registers have, the inputs 110 and 114 are mutually exclusive since each is selected to be the complement of the other. This means that whenever the system is in operation, there will be signal present in passages 110 and 118 or in passages 114 and 116. The addition of a clock pulse or other periodic input in passages 112 will, by momentum interchange with the existing signal, increase the signal in passages 116 or 118 at the discrete time intervals so that the reduction provided by the restrictions 120 and 122 will no longer be sufficient to prevent switching of the flip-flop. The man skilled in the art will recognize that the angular relationship of passages 116 and 118 to

8835 8840 8845 8850 8855 8860 8865 8870 8875 8880 8885 8890 8895 8900 8905 8910 8915 8920 8925 8930 8935 8940 8945 8950 8955 8960 8965 8970 8975 8980 8985 8990 8995 9000 9005 9010 9015 9020 9025 9030 9035 9040 9045 9050 9055 9060 9065 9070 9075 9080 9085 9090 9095 9100 9105 9110 9115 9120 9125 9130 9135 9140 9145 9150 9155 9160 9165 9170 9175 9180 9185 9190 9195 9200 9205 9210 9215 9220 9225 9230 9235 9240 9245 9250 9255 9260 9265 9270 9275 9280 9285 9290 9295 9300 9305 9310 9315 9320 9325 9330 9335 9340 9345 935

either of passages 110 and 114 will cause the strength of the signal received by the appropriate passage 116 or 118 to be substantially higher than the signal strength caused by signals in passages 110 and 114 without the clock pulse signal. This signal will be sufficiently strong so that strength reduction caused by the restriction 120 or 122 will not be sufficient to lower signal strength below the switching level of the bistable element 124. The coincidence of a clock signal with a signal in either of passages 110 and 114 will therefore set the output of the bistable to indicate in which of passages 110 and 114 the signal appeared when there was a substantially coincident clock signal pulse. Vent 111 is operative to exhaust excess fluid from region 101 as well as providing a fluid dump for extraneous fluid signals from passage 112.

Since the three input AND gate portion of the device utilizes momentum transfer principles, the angular relationship passages 110, 112, 114, 116 and 118 is of importance but may vary depending upon the expected momentum characteristics of the fluid used. This in turn will be controlled by the character of the fluid(s) and the velocity of signal propagation. The man of ordinary skill in the art will recognize these factors and will be able to determine, for his particular use, what the various angular relationships should be. Furthermore, the size of effect to be obtained by restrictions 120 and 122 will be determined by the strength of signals received by passages 110 and 114.

I claim:

1. A fluidic device comprising:

A fluid interaction region;

at least three fluid signal input passage means operative to introduce fluid into said interaction region;

fluid exhaust passage means arranged in an intercepting relation with said fluid input passages and operative to exhaust fluid from said interaction region;

said exhaust passage means so arranged as to intercept flow from a predetermined one and a predetermined combination of said input passage means;

flow restrictive means contained within said exhaust passage means selected to reduce fluid flow from said predetermined one of said input passage means to a level below the switching level of said bistable fluid element means, while flow from said predetermined combination of input passage means is reduced to a level above the

switching level of said bistable fluid element means; and a bistable fluid element means having opposed control ports in communication with said exhaust passage means.

2. The fluidic device as

5 2. The device as claimed in claim 1, wherein said bistable fluid element means is a fluidic flip-flop.

3. A fluidic shift register comprising:

a fluid interaction chamber;

10 first, second, and third fluid input passage means in communication with said interaction region for introducing fluid input signals thereinto;

fourth passage means having an inlet port in said chamber and arranged to intercept fluid input signals discharged from said first passage means single or in combination with fluid input signals discharged from said second passage means;

fifth passage means having an inlet port in said chamber and spaced apart from said inlet to said fourth passage means; said fifth passage means arranged to intercept fluid input signals discharged from said third passage means singly or in combination with fluid input signals discharged from said second passage means;

a bistable fluid element means having input means, control means, and output means;

a source of pressurized fluid in communication with said input means to produce a pressurized fluid output signal to said output means;

said fourth and fifth passage means in communication with said control means to selectively control the fluid output signals in said output means; and

amplitude reducing means in said fourth and fifth passage means operative to reduce the amplitude of said fluid signals therein by an amount sufficient to reduce the amplitude of a single fluid input signal below the switching level of said bistable fluid element means while maintaining means while maintaining the amplitude of combined fluid input signals above the switching level of said bistable fluid element means has been inserted.

4. The shift register as claimed in claim 3 wherein said first and third input passage means are connected to mutually exclusive sources of fluid input signals and said second input passage means is connected to a source of periodic fluid input signals.
